UNITED STATES PATENT OFFICE.

LAWRENCE GUY RITTER, OF CROMWELL, INDIANA.

PUMP-JACK.

1,250,018.

Specification of Letters Patent. Patented Dec. 11, 1917.

Application filed January 19, 1917. Serial No. 143,264.

To all whom it may concern:

Be it known that I, LAWRENCE GUY RITTER, a citizen of the United States, residing at Cromwell, in the county of Noble and 5 State of Indiana, have invented certain new and useful Improvements in Pump-Jacks; and I do hereby declare the following to be a full, clear, and exact description of the invention, such as will enable others skilled 10 in the art to which it appertains to make and use the same.

This invention relates to pump jacks, or a device for operating the reciprocatory pump rod of a pump structure, and the primary 15 object of the invention is to provide a pump jack structure which may be adjusted to fit pump rods of different strokes.

Another object of this invention is to provide a pump jack, which includes a plurality 20 of bars adapted for adjustable connection to each other and to a vertically reciprocable pump rod, which bars are operated through the medium of a rotatable spurred wheel, which wheel is in turn rotated by any 25 suitable power source and its teeth or spurs engage openings in a plate which is attached to one of the connecting bars for moving the bars vertically for reciprocating the pump rod.

30 With the foregoing and other objects in view, this invention consists in such novel features of construction, combination and arrangement of parts as will be hereinafter more fully described, illustrated in the accompanying drawings, and claimed.

35 In describing the invention in detail reference will be had to the accompanying drawings wherein like characters designate like and corresponding parts throughout the 40 several views, and in which:

Fig. 1 is an edge view of the pump jack.

Fig. 2 is a side elevation of the pump jack.

Fig. 3 is a side elevation of a part of the 45 pump jack showing the same in a different adjusted position to that shown in dotted lines in Fig. 2 of the drawings.

Fig. 4 is a section on the line 4—4 of Fig. 1, and

Fig. 5 is a cross section on the line 5—5 of 50 Fig. 1.

Referring more particularly to the drawings, 1 designates a support of any suitable type which is positioned in close proximity to the pump, upon which the pump jack is 55 to be used. This support has a suitable bearing 2 carried thereby. The bearing 2

rotatably supports a shaft 3 upon one end of which is mounted a pulley 4. A belt 5 travels about the pulley 4, for rotating the pulley, and consequently the shaft 3 by any 60 suitable power source.

The shaft 3 has a wheel 6 mounted thereon which is provided with a plurality of radiating fingers or spurs 7. The fingers or spurs 7 are provided for extending through 65 openings 8 which are formed in a vertical row, and in vertically spaced relation to each other in a plate 9 which plate is supported by suitable braces 10. The braces 10 are attached to straps 11, the ends of which are 70 connected through the medium of bolts or analogous fastening devices 12 and plates 13 which engage the inner surfaces of the ends and hold them in the proper spaced relation. The straps 11 bow outwardly so 75 as to provide space between the sides of the plate 9 and the inner side of the straps, to allow the hub portion of the wheel 6 to pass downwardly between the plate 9 and the straps 11, so that the rotation of the wheel 6 80 will move the plate 9, and consequently the straps 11 vertically. The straps 11 are provided with longitudinally extending slots 14 which permit the spurs 7 to project beyond the outer surface of the straps. The straps 85 11 are attached to a bar 20 of the pump jack structure by means of U-shaped bolts 21, so that the rotary movement of the shaft 3, which is transmitted to the plate 9 in a reciprocatory movement will be transmitted to 90 the bar 20 for reciprocating the bar 20. The bar 20 is connected through the medium of a bar 22 to the reciprocatory pump rod 23, as clearly shown in Fig. 1 of the drawings.

In Figs. 2 and 3 of the drawings, a stroke 95 regulating structure is illustrated which is employed for connecting the bar 20 to the pump rod 23. The stroke starting structure, which is generically indicated by the numeral 25 comprises a bar 26 which is pivotally connected to the bar 20.

The bar 26 is provided with a plurality of longitudinally spaced openings 27, through which a bolt 28 extends for connecting the bar 22 to a relatively short bar 29. The relatively short bar 29 is connected as shown at 30 to the bar 20 and as shown at 31 to a bar 32. The latter bar is connected as shown at 33 to the pump rod 23. By varying the adjustable connection between the bar 26 and the relatively short bar 29 and also varying the angles of the bars 26, 29, and 110

32, the distance between the shaft 3 and the point of connection between the bar 20 and the pump rod 23 may be varied for shortening or lengthening the stroke of the pump 5 rod.

The rotary movement of the shaft 3 will be converted into reciprocatory movement, and transferred to the bar 20 by the engagement of the teeth or spurs 7 through the 10 openings 8 of the plate 9, and through the medium of the straps 11. The vertical reciprocatory movement of the bar 20 will be transmitted to the pump rod 23, either through the medium of the bar 22 or through 15 the medium of the bars 26, 29 and 32 as herebefore described, for reciprocating the pump rod and operating the pump.

From the foregoing description taken in connection with the accompanying drawings, 20 the advantages of construction and of the method of operation of the improved pump jack will be readily apparent to those skilled in the art to which this invention appertains, and while in the foregoing description, the 25 principle of the operation of this invention has been described together with various features of construction, it is to be understood that certain minor features of construction, combination and arrangement of 30 parts may be altered to suit practical conditions provided such alterations are comprehended within the scope of what is claimed.

What is claimed is:

1. In a pump jack structure, the combination, of: a pump rod, a rotatable shaft, a wheel carried by said shaft, a plurality of radiating spurs formed circumferentially about said wheel, a plate provided with a plurality of vertically spaced openings 40 adapted to receive said spurs for reciprocating the plate by the rotary movement of said wheel, a pair of guard plates extending about said first named plate for guarding and guiding the operation of said wheel, a bar, U-shaped bolts connecting said bar through said guard and guide straps for transmitting a reciprocatory movement from said first named plate to said bar, and means 45 for connecting said bar to said pump rod.

2. In a pump jack structure, the combination, of:

Copies of this patent may be obtained for five cents each, by addressing the "Commissioner of Patents, Washington, D. C."

tion, of a pump rod, a rotatable shaft, a wheel carried by said shaft, a plurality of radiating spurs formed circumferentially about said wheel, a plate provided with a plurality of vertically spaced openings 5 adapted to receive said spurs for reciprocating the plate by the rotary movement of said wheel, a pair of guard plates extending about said first named plate for guarding and guiding the operation of said wheel, a bar, 60 U-shaped bolts connecting said bar through said guard and guide straps for transmitting a reciprocatory movement from said first named plate to said bar, and adjustable means connected to said bar and adapted for 65 connection to a pump rod, said adjustable means being constructed for varying the reciprocatory stroke transmitted to said pump rod by said bar.

3. In a pump jack structure, the combination, of: a pump rod, a rotary shaft, a spurred wheel carried by said shaft for rotation therewith, a plate provided with a plurality of openings for receiving the spurs upon said wheel for reciprocating the plates by 70 the rotary movement of said shafts, a pair of guard plates extending about said first named plate, said guard plates being provided with longitudinally extending slots 75 for guiding the movement of said spurred wheel, a bar, means connecting said bar to said guard plate, a second bar pivotally connected to said first named bar, a relatively short bar pivotally and adjustably connected to the lower end of said second named bar, 80 and a fourth bar pivotally connected to one end of said relatively short bar and adapted for connection with a pump rod, said second mentioned relatively short and fourth bars being pivotally and adjustably connected for 85 regulating the length of the reciprocatory stroke transmitted to said pump rod by said first named bar.

In testimony whereof I affix my signature in presence of two witnesses.

LAWRENCE GUY RITTER.
